ROLLER ROCK BIT

Alfred C. Catland, Alhambra, Calif., assignor to
 Globe Oil Tools Company, Los Nietos, Calif.,
 a corporation of California

Application July 6, 1936, Serial No. 88,989

12 Claims. (Cl. 255—71)

This invention relates to a well drilling tool and relates more particularly to a roller rock bit for use in the rotary method of well drilling. A general object of this invention is to provide a practical, improved and particularly effective roller rock bit.

Another object of this invention is to provide a roller rock bit embodying a novel and simplified arrangement of parts which promotes the general efficiency of the tool and makes it inexpensive and easy to service.

Another object of this invention is to provide a roller rock bit embodying sets of inner cutters rotatably supported on a single angular pin supported intermediate its ends by a novel removable stud.

Another object of this invention is to provide a roller rock bit in which the several cutter supporting legs or shanks are integral parts of the body.

Another object of this invention is to provide a roller rock bit of the character mentioned in which the shafts or pins supporting the outer cutter bushings are subjected to little or no shear strain and, therefore, are not liable to fail when the tool is in operation.

Another object of this invention is to provide a roller rock bit in which the removable parts are securely and dependably locked against loss and displacement when the tool is in operation and yet may be easily removed for replacement, etc.

Another object of this invention is to provide a roller rock bit embodying improved means for flushing the several roller cutters.

The various objects and features of my invention will be fully understood from the following detailed description of a typical preferred form and application of the invention, throughout which description reference is made to the accompanying drawings, in which:

Fig. 1 is a central longitudinal detailed sectional view of the bit provided by this invention, being a view taken as indicated by line 1—1 on Fig. 2. Fig. 2 is a fragmentary vertical detailed sectional view taken substantially as indicated by line 2—2 on Fig. 3. Fig. 3 is a reduced side elevation of the bit and Fig. 4 is a fragmentary transverse detailed sectional view taken as indicated by line 4—4 on Fig. 1.

The improved roller bit of the present invention includes, generally, a body 10, two sets of inner roller cutters 11 and 12, means 13 rotatably supporting the cutters 11 and 12, two outer cutters 14, means 15 rotatably mounting the outer cut-

ters 14, and means 16 for flushing the cutters 11, 12 and 14.

The shank or body 10 is provided to carry the cutters and the various other parts of the tool. The body 10 is adapted to be connected with the lower end of a well drilling string and is provided at its upper end with suitable connecting means. In the particular case illustrated a tapered screw threaded socket 17 is provided in the upper end of the body 10 to receive the threaded pin 18 of a drill collar or the like. The body 10 is an integral member having a cylindrical upper part through which the socket 17 extends. The lower portion of the body 10 is preferably of enlarged diameter and is open at its lower end. Depending parts or wings are provided on the lower end of the body 10 to carry the cutter mounting means 13 and 15. Legs or wings 19 project downwardly from the body 10 at diametrically opposite points. The wings 19 project downwardly and slightly outwardly. Raised or inwardly projecting parts are provided on the inner sides of the wings 19 adjacent their lower ends and present substantially vertical thrust surfaces 20. A flat downwardly facing shoulder 21 is provided at the lower end of each thrust surface 20. The lower ends or wings 19 are preferably bevelled downwardly and inwardly as clearly illustrated in Fig. 2.

The invention includes wings 22 projecting downwardly and outwardly from the lower portion of the body 10 at points substantially 90° from the above described legs 19. Raised surfaces 23 are provided on the inner sides of the legs 22. The surfaces 23 are inclined downwardly and outwardly relative to the central longitudinal axis of the bit. Flat faces or shoulders 24 are provided on the lower ends of the wings 22 and are normal to the thrust surfaces 23. The spaced legs 19 and 22 surround or define a relatively large socket-like space at the lower end of the body 10. An integral partition or wall 25 separates the socket 17 from the space or opening in the lower end of the body 10. In accordance with the invention a web 26 depends from the wall 25. The web 26 is an integral part of the body 10 and lies in and adjacent the central vertical plane of the body. The web 26 is relatively thin and its opposite side edges which oppose the wings 22 slope downwardly and outwardly. Inner wings 27 form integral continuations of the web 26. The wings 27 are inclined downwardly and outwardly relative to the central vertical axis of the tool and present raised thrust surfaces 28 which are spaced from and

parallel with the surfaces 23. Flat shoulders 29 occur on the lower ends of the wings 27. The shoulders 29 are preferably normal to the thrust surfaces 8.

5 The cutters 11 and 12 are rotatably supported in the open lower end of the body 10 to act on the inner portion of the bottom wall of the well bore. The inner cutters are arranged in sets or pairs each pair comprising a relatively 10 small cutter 11 and a larger cutter 12. The cutters 11 and 12 are in the nature of roller cutters, the cutters 11 being cylindrical cutters and the cutters 12 being frusto-conical cutters. The relatively small cutters 11 have central longitudinal 15 openings 30 and peripheral cutting teeth 31. The cutting teeth 31 may be straight and axial. In the preferred construction the inner ends of the teeth 31 project beyond or overhang the inner ends of the cutters 11. The opposite ends of 20 the cutters 11 may be flat and normal. The frusto-conical inner cutters 12 have central longitudinal openings 32 and flat normal ends. Peripheral cutting teeth 33 are provided on the cutters 12. The teeth 33 may be straight and 25 axial or may be spiralled if desired. The teeth 33 project beyond or overhang the large ends of the frusto-conical cutters 12. The cutters 12 are considerably larger than the cutters 11, their small ends being larger in diameter than the cutters 11.

The means 13 operates to dependably support the sets of inner cutters 11 and 12 for rotation about downwardly and outwardly inclined axes. The cutter mounting means 13 includes 35 a substantially transverse shaft or pin 34. The pin 34 is angular having its major end portions inclined downwardly and outwardly. The intermediate portion 34a of the pin 34 is substantially horizontal. The opposite extremities 35 of the 40 pin 34 are reduced in diameter. It is to be understood that the pin 34 may be cylindrical in transverse cross section. The pin 34 extends transversely between the two opposite wings 19 and its intermediate portion 34a is at the vertical center of the tool. Studs or screws 36 are passed inwardly through downwardly and outwardly inclined openings 37 in the legs 19 and are threaded in openings 38 in the opposite ends of the pin 13 to connect the ends of the pin with 45 the legs 19. The screws 36 have heads 36a countersunk or recessed in the outer ends of the openings 37. The invention provides means for dependably securing the screws 36 against unthreading. Edge or corner portions 39 of the 50 heads 36a are peened into notches in the outer sides of the legs 19 to lock the screws 36 against rotation and unthreading.

The invention provides means for supporting the pin 34 intermediate its ends. A central vertical opening 40 is provided in the body web 26. The opening 40 extends downwardly from the socket 17 to the lower end of the web 26. A downwardly facing annular shoulder 41 is provided on the wall of the opening 40. The cutter mounting means 13 includes a stud 42 arranged longitudinally in the opening 40. The stud 42 has a shoulder 43 adapted to bear upwardly against the shoulder 41. A transverse opening 44 is provided in the lower portion of the stud 42 65 and receives the straight intermediate portion 34a of the pin 34. A lock pin 45 is arranged through transverse openings in the pin 34 and the stud 42 to secure the pin to the stud. The supporting stud 42 projects upwardly into the 70 socket 17 and a nut 46 is threaded on its pro-

jecting upper end. A washer 47 is provided under the nut 46. The nut 46 may be locked in place by a cotter key, or the like. The nut 46 urges the stud 42 upwardly so that its shoulder 43 is clamped against the shoulder 41. The stud 42 serves to rigidly and dependably support the pin 34 between its ends. Thus the pin 34 is supported at its opposite ends and at its middle portion.

The cutters 11 are rotatable on the pin 34 adjacent the opposite sides of the stud 42. In practice the inner cutters 11 may be directly rotatably supported on the pin 34. The stud 42 is preferably provided with downwardly convergent thrust surfaces 48 against which the inner ends of the cutters 11 may bear. The projecting inner ends of the teeth 31 overhang a substantial portion of the lower end of the stud 42 to prevent the engagement of the earth formation with the stud. The teeth 31 projecting inwardly below the end of the stud 42 act on the earth formation immediately adjacent the center of the well bore. The cutters 12 are rotatably supported on the pin 34 between the cutters 11 and the wings 19. Roller bearings 49 may be provided to rotatably support the cutters 12 on the pin 34. Thrust washers 50 are interposed between the outer ends of the cutters 12 and the wings 19. The washers 50 are arranged on the reduced end portions 35 of the pin 34 and their inner surfaces are engaged by the outer ends of the cutters 12. The outer sides of the washers 50 cooperate with the thrust surfaces 20. Extensions or lugs 51 are provided on the washers 50 and cooperate with the shoulders 21 to hold the washers against rotation and to transmit the operating thrusts directly to the wings 19. The lower ends of the washers 50 and their lugs 51 may be bevelled off flush with the lower ends of the wings 19.

In assembling the inner cutters 11 and 12 on the body 10, the pin 34 is first entered in the opening 44 and is secured to the stud 42 by the pin 45. The cutters 11 and 12 are then properly arranged on the pin 34 and the washers 50 are placed on the end portions 35 of the pin. The washers 50 may be force-fitted or press fitted on the end portions 35 to retain the cutters 11 and 12 on the pin 34 and thus facilitate the handling of the assembly. The stud 42 is then passed upwardly through the opening 40 at which time the lugs 51 are brought against the shoulders 21. The screws 36 are then threaded in place and the nut 46 is threaded on the stud 42 to secure the cutter supporting assembly to the body 10.

The outer cutters 14 are in the nature of frusto-conical roller cutters. Each cutter 14 has a central longitudinal opening 52. The opposite ends of the cutters 14 are preferably flat and normal. Suitable peripheral cutting teeth 53 are provided on the outer cutters 14. The teeth 53 may be straight or spiralled, as desired. The outer corners of the teeth 53 are preferably bevelled off while the inner ends of the teeth 53 preferably overhang or project inwardly from the inner ends of the cutters 14.

The means 15 rotatably support the inner cutters 14 between the opposed wings 22 and 27. The cutter supporting means 15 include bushings 54. The bushings 54 are arranged between the adjacent opposed wings 22 and 27 and are inclined downwardly and inwardly, having their longitudinal axes normal to the surfaces 23 and 28. The cutters 14 may be rotatably supported on

the bushings 54 through suitable roller bearings 55. The cutters 14 are arranged with their large ends outermost and being rotatable about inclined axes the bevelled outer ends of their teeth 53 are substantially vertical when the teeth come into engagement with the formation. Thrust flanges 56 are provided on the inner ends of the bushings 54. The flanges 56 constitute thrust washers for transmitting operating thrusts from the inner ends of the cutters 14 to the wings 27. The outer sides of the flanges 56 are adapted to bear on the surfaces 28 while the inner ends of the cutters 14 and the bearings 55 bear on the inner surfaces of the flanges. Each flange 56 has a lug 57 cooperating with a shoulder 29 to prevent rotation of its bushing 54 and to transmit upward thrusts directly to the wings 27. The outer end portions 54^a of the bushings 54 are reduced in diameter and thrust washers 58 are provided on the reduced portions 54^a. The washers 58 may be pressed or force-fitted on the reduced bushing portions 54^a to retain the cutters 14 and the roller bearings 55 on the bushings to facilitate the handling and transporting of the cutter assemblies. The washers 58 are engageable by the outer ends of the rollers 55 and the cutters 14 and bear on the surfaces 23 to transmit the end thrusts directly to the body wings 22. Extensions or lugs 59 are provided on the washers 58 and cooperate with the shoulders 24 to prevent rotation of the washers and to transmit upward thrusts to the wings 22. The lower outer corners of the washers 58 and their lugs 59 are bevelled off so that they do not contact the side wall of the well bore. The cutter supporting means 15 includes pins 60 for holding the bushings 54 in place and for tying together the adjacent legs 22 and 27. Aligned downwardly and inwardly inclined openings 61 and 61^a are provided in the legs 27 and 22 respectively. The pins 60 are passed outwardly through the openings 61 in the legs 27 and are threaded in the openings 61^a in the legs 22. Suitable heads 62 are provided on the inner ends of the pins 60 and are countersunk in the inner ends of the openings 61. Means are provided to prevent rotation and unthreading of the pins 60. The outer end parts of the pins 60 are reduced and unthreaded. Extreme end or corner portions 63 of the pins 60 are peened into notches in the legs 22 to prevent unthreading of the pins. The cutters 14 rotatably mounted as just described project downwardly beyond the lower ends of the legs 22 and 27 to act on the outer portion of the bottom wall of the well bore and to cut the well bore to gauge. The inclination of the cutters 14 is such that the lower edges of their teeth 53 are inclined downwardly and inwardly as the teeth come into contact with the earth formation. The cutters 12 and 14 are related so that they overlap one another in their action on the earth formation and the lower ends of the legs 27 and the washers 56 do not come into contact with the earth formation. The means 16 for flushing the cutters 11, 12 and 14 provides for the full effective flushing of the several cutters. The flushing means 16 includes or provides a plurality of circumferentially spaced openings 70 in the body wall 25. The openings 70 extend downwardly from the bottom of the socket 11 to the lower surface of the wall 25. The openings 70 are cylindrical and each has an upwardly facing annular shoulder 71 adjacent its lower end. The longitudinal axes of the openings 70 are inclined downwardly and outwardly. In accordance with the invention the openings 70

are positioned so that one opening is above each outer cutter 14 and so that an opening 70 is above each pair of inner cutters 11 and 12.

The means 16 further includes flow nipples or chokes 72 arranged in the openings 70. The chokes 72 are cylindrical members entered in the openings 70 from their upper ends. The chokes 72 closely fit the openings 70 and their lower ends bear on the shoulders 71. Each choke 72 has a longitudinal fluid discharge opening 73. The openings 73 are cylindrical at their upper ends and are transversely elongated at their lower ends. The walls of the openings 73 are smooth and gradually rounded to provide for the ready discharge of the circulation fluid. The chokes 15 72 are positioned so that the lower ends of their openings 73 are radially elongated and have their major transverse axes substantially vertically aligned with the axes of the cutters 14 and the axes of rotation of the cutters 11 and 12. Thus 20 the fluid discharge openings 73 direct transversely elongated streams of circulation fluid against the cutters, which streams extend throughout the lengths of the cutters to effect the full flushing of the cutters. 25

The washer 47 constitutes a means for holding the chokes 72 in place. The washer 47 contacts the inclined upper surfaces of the chokes 72 adjacent their peripheral edges to hold the chokes down and prevent their rotation. The lower ends 30 of the body socket 11 is open and receives the circulation fluid from the well drilling string S. This circulation fluid passes from the socket 11 through the openings 73 at an increased velocity. The openings 73 direct the circulation fluid 35 downwardly against the teeth of the cutters 11, 12 and 14 to clear them of mud and cuttings.

It is believed that the operation of the improved roller bit provided by this invention will be readily apparent from the foregoing detailed description. In operation the tool is connected with the lower end of the drilling string S which is rotated and fed downwardly. During rotation of the string S the cutters 11, 12 and 14 act or roll on the formation at the bottom of the well 40 45 bore to crush or cut away the same. The cutters 11 and 12 being rotatable about downwardly and outwardly inclined axes act on the upper surface of a central conical mound on the bottom wall of the well bore. The cutters 11 being smaller in 50 diameter than the cutters 12 provide a step or shoulder on this conical mound. The inner cutters 11 and 12 acting on the stepped conical mound in the center of the well bore act to center and stabilize the rotating bit. It will be noted 55 that the cutters 11 and 12 are adapted to engage substantially the entire inner portion of the well bore. The outer cutters 14 pursue an annular course surrounding and overlapping the course of the cutters 12 to cut away the outer portion of 60 the well bore. The cutters 14 also operate to engage the side wall of the well to cut the well to gauge. Circulation fluid is pumped downwardly through the string S and discharges from the choke openings 73. As described above, the fluid 65 is discharged from the openings 73 in inclined transversely elongated streams which flush the cutters 11, 12 and 14 throughout their lengths.

The cutters and the other replaceable parts are securely and dependably connected with the body 70 10 so that they cannot become displaced during operation of the tool. The pin 34 supporting the inner cutters is secured to the wings 19 at its outer end and is supported intermediate its ends by the stud 42. The screws 36 securing the ends 75

of the pin 34 to the legs 19 tie the legs to the pin and lend rigidity to the assembly. The pins 60 hold the bushings 54 in their proper inclined positions and serve to tie the legs 22 to the legs 27. The bushings 54 and the washers 58 receive the thrusts from the cutters 14 so that the pins 60 are subjected to very little wear and pressure. The various wear receiving parts of the tool may be easily and quickly replaced to recondition the tool for further use.

Having described only a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. A roller bit including, a body having wings projecting from its lower end, a shaft extending between the wings and having oppositely inclined end portions, means securing the ends of the shaft to the wings, a depending stud removably carried by the body and having an opening carrying the intermediate portion of the shaft, and roller cutters on the inclined portions of the shaft.

2. A roller bit including, a body having wings projecting from its lower end, a shaft extending between the wings and having oppositely inclined end portions, screws securing the ends of the shaft to the wings, a depending stud on the body having an opening carrying the intermediate portion of the shaft and cutters rotatable on the inclined portions of the shaft.

3. A roller bit including, a body having wings projecting from its lower end, a shaft extending between the wings and having oppositely inclined end portions, means securing the ends of the shaft to the wings, a removable stud depending from the body and having an opening carrying the intermediate portion of the shaft, downwardly convergent bearing surfaces on the stud at the ends of the opening, and roller cutters rotatable on the inclined portions of the shaft and bearing on said surfaces.

4. A roller bit including, a body, wings projecting from the lower end of the body and having substantially vertical inner sides, a shaft extending between the wings and having oppositely inclined end portions, means connecting the ends of the shaft to the wings, means supporting the shaft intermediate its ends, roller cutters rotatable on said inclined portions of the shaft, and thrust washers between the inner sides of the legs and the ends of the adjacent cutters, each washer having convergent sides, one bearing on the inner side of a leg, the other engageable by a cutter.

5. A roller bit including, a body having wings projecting from its lower end, a shaft extending between the wings and having oppositely inclined end portions, means securing the ends of the shaft to the wings, a depending stud removably carried by the body and having an opening carrying the intermediate portion of the shaft, a lock pin arranged through transverse openings in the stud and shaft, and roller cutters on the inclined portions of the shaft.

6. A roller bit including, a body having a socket in its upper end and an opening extending downward from the socket, legs depending from the body, a stud arranged in said opening and projecting from the lower end of the body, the pro-

jecting portion of the stud having a horizontal opening, a pin having a horizontal portion carried in said horizontal opening and downwardly and outwardly inclined portions extending toward the legs, means tying the ends of the pin to the legs, and roller cutters rotatable on the inclined portions of the pin.

7. A roller bit including, a body having wings projecting from its lower end, a shaft extending between the wings and having oppositely inclined end portions, means securing the ends of the shaft to the wings, a depending stud removably carried by the body and having an opening carrying the intermediate portion of the shaft, and roller cutters on the inclined portion of the shaft having cutting teeth extending inwardly at the lower end of the stud.

8. A well bit including, a body having diametrically opposite depending wings, a web on the body projecting downwardly between the wings, inner wings on the web spaced from and opposing the first mentioned wings, roller cutters supported between the adjacent opposed wings for rotation about inclined axes, parts integral with the body and projecting downwardly from the body at points spaced from the first mentioned wings, there being an opening in the web, a removable stud carried in the opening, a transverse pin supported between its ends by the stud, means tying the ends of the pin to the said parts, and roller cutters on the pin.

9. A well bit including, a body having diametrically opposite depending wings, a web on the body projecting downwardly between the wings, inner wings on the web spaced from and opposing the first mentioned wings, roller cutters supported between the adjacent opposed wings for rotation about inclined axes, parts projecting downwardly from the body at points spaced from the first mentioned wings, there being an opening in the web, a removable stud carried in the opening, the stud having a transverse opening, a transverse pin having its intermediate portion carried in the opening of the stud and being inclined downwardly and outwardly from the stud, cutters rotatable on the pin, and means tying ends of the pin to the said parts.

10. A well bit including, a body having a fluid chamber and spaced openings extending from said chamber to an external surface, roller cutters rotatably supported by the body, chokes in said openings having transversely elongate openings discharging correspondingly shaped streams against the cutters, and a single means retaining the several said chokes in the openings.

11. A well bit including, a body having a fluid chamber and spaced openings extending from said chamber to an external surface, roller cutters, means supporting the cutters on the body including, a part projecting into said chamber, chokes in said openings discharging streams of fluid against the cutters, and a member on said part retaining the chokes in the openings.

12. A well bit including, a body having a fluid chamber and spaced openings extending from said chamber to an external surface, roller cutters, means supporting the cutters on the body including, a part projecting into said chamber, chokes in said openings discharging streams of fluid against the cutters, and a retaining nut on said part securing the same to the body and holding the chokes in the openings.
